Monroe Guett Inventor
By Hunt Litholoid Attorney

UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

HINGE.

1,251,773.

Specification of Letters Patent.

Patented Jan. 1, 1918.

Application filed January 5, 1917. Serial No. 140,684.

To all whom it may concern:

Be it known that I, MONROE GUETT, a citizen of the United States, residing at Hartford, in the county of Hartford and 5 State of Connecticut, have invented certain new and useful Improvements in Hinges, of which the following is a specification.

This invention relates to hinges. While a hinge involving the invention is susceptible 10 of general use, it is of particular utility, however, for associating a swinging member and its supporting part where these elements are of sheet metal. The swinging member and the supporting part are pivotally connected and the pivot or pivots are maintained in assembled relation by staking the stock of the swinging and supporting parts over the pivot or pivots in such way as to not sacrifice strength.

20 In the drawings accompanying and forming part of the present specification I have shown in detail one convenient form of embodiment of the invention which I will set forth fully in the following description. I 25 do not restrict myself to this particular disclosure; I may depart therefrom in several respects within the scope of the invention defined by the claim following said description. In this form of embodiment of the invention the same is shown incorporated in a 30 face plate such as is used in electrical work.

Referring to said drawings:

Figure 1 is a front view and

Fig. 2 is a rear view of such a face plate 35 involving the invention.

Fig. 3 is a central vertical section of the plate as seen from the left in Fig. 3, showing the door open.

40 Figs. 4 and 5 are longitudinal sections on the lines 4—4 and 5—5 respectively of Fig. 2, looking in the direction of the arrows and which are on a larger scale than the other views.

Like characters refer to like parts throughout the several views.

45 As I have already observed the invention is capable of use in various ways, although it is of particular importance when incorporated in a face plate supporting a swinging member such as a door. I have illustrated such a face plate, the same being denoted by 2, and it supports a door as 3 constituting a convenient swinging member which

can be hingedly mounted in accordance with the invention. The face plate and door are 55 made of sheet metal and the former has an opening 4 in which the door is received when closed as shown in Figs. 1, 2 and 5, but which may be swung open as illustrated in Fig. 3. This face plate generally covers 60 a box containing a socket, to which may be connected a plug, and this connection is obtained by the opening of the door 3. This door is shown only partly open in Fig. 3. When the plug is disconnected from its 65 socket, the door is shut as shown in said Figs. 1, 2 and 5. Such a face plate provided with a door functioning in the manner set forth is comparatively old in the electrical art, and it is quite common also to make 70 these parts of sheet metal. While I have shown only one door, this is merely a detail, because more may be provided, the invention not concerning this point nor necessarily the shape of the door. The form of door I 75 have shown, however, is a desirable one, the body of the door being practically circular and having a radial circumferential projection 5 and as observed being of a shape corresponding to the opening 4 which is practically of key-hole form, the radial slot 6 extending from the circular portion of the hole or opening 4 receiving the projection 5.

To connect the door 3 with the face plate 2 or equivalent, I have shown two pivot pins 85 7 and 8, these pivot pins being cylindrical. The face plate has on its inner side the grooves 9 and 10 to receive the respective pins. The outer ends of the said grooves, it will be noticed are closed, the closed ends 90 extending short of the side edges of the face plate. The door has on its inner face grooves 11 and 12 to receive the respective pivot pins. It will be noticed that the inner ends of these grooves 11 and 12 are also 95 closed and that they are spaced or separated from each other, the stock of the door between the said grooves 11 and 12 being uncut and presenting an effective reinforcing portion to offset the weakening of the door 100 which is occasioned by the formation of these grooves. The grooves can be formed in the door in any desirable manner as by a mill cut or by the use of dies. The grooves are circular in cross section, their radius 105 agreeing approximately with that of the re-

spective pivot pins 7 and 8. The several grooves are coaxial, the inner end of the grooves 7 being opposite the outer end of the groove 11 and the inner end of the groove 5 10 being opposite the outer end of the groove 12; the two pivot pins 7 and 8, therefore, are coaxial.

I hold the two pivot pins 7 and 8 in place by staking the stock of the face plate and 10 door respectively thereover. It is old to pivotally connect a door with a support by pivot pins set in alined grooves in the two parts and to maintain the pins in proper 15 relation with the support and door by staking the stock of said parts over the pins. Where in the old construction this is used in a face plate and a door employed in the manner already set forth, the face plate and 20 door are of comparatively thick stock and the stock of these two parts is turned over 25 the pivots by staking, the stock thus staked out, however, being cut at right angles to the parts which is feasible owing to the thickness to which I have referred. I am 30 enabled to use an exceedingly thinner face plate and door of sheet metal and yet can hold the pivot pins in position by staking without appreciably sacrificing strength.

I have already referred to the fact that 35 there is an important advantage in leaving the stock between the grooves 11 and 12 uncut. While according to one phase of the invention the door might be grooved all the way across, still there is a decided advantage 40 in making two grooves and provision for a reinforcing neck as it were between them. Another equally important feature of the invention is the way in which I stake the pivots in place as will hereinafter more particularly appear.

I desire to call attention to the fact that 45 the several grooves are of such depth that the outer portions of the two pivot pins are virtually flush with the corresponding surfaces, which are the back in the present case, of the face plate and door respectively as illustrated in both Figs. 4 and 5. The material between the pins and the front of the face plate and door is as a consequence 50 quite thin, as indicated in both said Figs. 4 and 5 but the staking is done in such way that although the material at the points indicated be quite thin, the strength of the finished structure is practically in no wise affected.

The face plate 2 on its rear is staked out 55 as at 13 and 14, and 15 and 16 respectively to engage the respective pivot pins 9 and 10, these staked over parts 13, 14, 15 and 16 60 in the construction shown solidly embracing the pivots near their outer ends. The door is staked out as at 17 and 18, and 19 and 20, the staked out portions of the door 65 overlying the pins near their inner ends but not necessarily, however, closely hug-

ging the pivots. The construction in question might be reversed, although by providing that set forth the swing of the door on the pivots or pins 7 and 8 is possible. The only difference, therefore, in the construction shown between the stakings of the face plate and those of the door is that the former closely embraces the pivots or pins, while the latter do not which is a way of obtaining the necessary swinging motion of 75 the door. Obviously, therefore, the pivots do not turn with respect to the face plate 2 or analogous member.

In the old staked out construction to which I have hereinbefore referred, the staking was done at right angles to the door and its support at the pin or pivot receiving grooves. This is feasible where the parts in question are of a certain thickness, but where as in the present case they are quite thin, 80 this is practically, and I might correctly say, actually impossible from a manufacturing standpoint. In the two sectional views 85 4 and 5 the advantage of the new construction is brought out forcefully. In these two 90 figures the staked out portions 15 and 16 and 19 and 20 respectively appear, but they are exactly like the corresponding parts on the opposite side of the article. It will be seen that these staked out lugs or projections 95 15, 16, 19 and 20 have their bases removed from the adjacent grooves and that the staked out parts are not in parallelism with the side walls of the groove but are oblique thereto. In other words I stake out the skin portions 100 of the stock commencing at points removed from the side walls of the respective grooves, the staking cuts being made at acute angles rather than at right angles to the rear face of the face plate and door respectively, the 105 staked over parts being not at right angles to but at acute angles to the rear or other surfaces of the face plate and door respectively. It might in fact be proper to say that the several staked out lugs of which in 110 the present case there are four pairs, are transverse to the respective grooves, although not necessarily at right angles thereto.

It is desirable to call attention to some 115 of the striking differences between the present construction and what I have conceded to be old. In the old construction it is true that the stock of both the door and its support are staked over the pivot pins, but the 120 staking cuts are made in a direction at right angles to both the door and the face plate. In the present case my staking cuts to force the stock over the pin are made by pressures applied to the face plate and the door at 125 acute angles to these parts. The lugs or projections produced by these staking out operations in my case extend outward beyond the faces of the parts in which they are made, whereas in the old construction 130

the staked over parts are inside of said faces. In staking out opposite lugs the tools which perform the necessary action approach on converging angles which as will 5 be understood, are acute to the rear surface of the plate and door. I have already called attention to the fact that the outer sides of the pivots or pins are practically flush with the corresponding surfaces of the door and 10 face plate, and in this respect I differ from the old construction, because the outer surfaces of the pins or pivots therein are below the corresponding surfaces of the door and plate and the staked out lugs are also below 15 said surfaces.

It will be evident that the door and the support hereinbefore described are grooved in corresponding faces and that the grooves are in alinement and their ends open. A 20 pivot pin is set in the respective grooves, the skin portion of both the door and the support being cut therefrom at a point removed from the respective grooves, and said skin portion being bent over the pin on both 25 the door and the support. The cuts are at opposite sides of the respective grooves and are on converging angles acute to the back faces of the door and the support. By reason of this construction I can utilize very 30 thin stock for the formation of both the door and the support, thinner in fact than is now so far as I am aware possible. This is a consideration of the utmost importance, especially where the parts are made from

sheet brass or similar material which is relatively speaking comparatively expensive. 35

What I claim is:

The combination of a door and its support, both of which are made from sheet metal, the support having an opening, the door fitting in the opening and when closed having its front face in the plane of the front face of the support, the door having distinct grooves and the support also having grooves at opposite sides of the opening, the 40 several grooves being in alinement transversely of the support and their outer ends being open, the inner ends of the grooves in the door being closed and spaced from each other, the grooves being arranged respectively in pairs, and the open ends of the grooves of the respective pairs being in register, and pivot pins set in the grooves of the doors and the support respectively, the skin portion of both the door and the support being cut therefrom at points removed 45 from the respective grooves, the skinning cuts being on forwardly converging angles which are acute to the rear face of the door and the support, and the skin portions being 50 bent over the pins on both the door and the support. 55

In testimony whereof I affix my signature in the presence of two witnesses.

MONROE GUETT.
